H. DENNERT

SHOE

Filed Nov. 22, 1924

INVENTOR:

Henry Dennert.

BY *Arthur N. Israel*,
ATTORNEY.

UNITED STATES PATENT OFFICE.

HENRY DENNERT, OF NEWPORT, KENTUCKY.

SHOE.

Application filed November 22, 1924. Serial No. 751,453.

To all whom it may concern:

Be it known that I, HENRY DENNERT, a citizen of the United States, and resident of Newport, in the county of Campbell,

5 State of Kentucky, have invented certain new and useful Improvements in Shoes, of which the following is a full, clear, and exact description, reference being had to the accompanying drawings, forming a part of

10 this specification.

My invention relates to shoes and has particular reference to the provision of straps or braces for causing the shoe to fit more snugly about the arch and instep of the

15 foot, and also to brace and strengthen said parts.

The principal object of this invention is to provide simple and efficient means built into the shoe at the time of its construction,

20 whereby the same is caused to fit more tightly to the foot and to strengthen and support the arch and instep thereof.

Further objects of the invention will appear from the following detailed description thereof.

In the drawings:

Figure 1 is a perspective of a shoe constructed in accordance with this invention, the novel features being shown in broken

30 lines.

Figure 2 is a vertical section at the shank of the shoe.

Figure 3 is a horizontal section near the top of the shoe.

35 The novel features of the present invention consist in building into the shoe straps 1 and 2. The strap 1 is sewed into the shoe construction between the insole and outer sole and extends upwardly between the lining and upper of the shoe. The lining is slit, as shown at 3—3, so that the ends of the strap 1 may extend therethrough; said ends are provided with eyes 4—4 through

40 which the shoe lace 5 may be threaded before passing through the eyes of the shoe near the upper portion thereof. The eyes

4 are so placed as to fall a little bit short of the eyes of the shoe so that when the lace is tightened the strap 1 will be drawn firmly about the arch of the foot.

50 The strap 2 is built around the counter of the shoe between the upper leather and the lining, and the lining is provided with slits 6—6 through which the ends of said strap extend. The ends of the strap 2 are provided with eyes 7—7 which are adapted normally to be a little bit short of the corresponding eyes 8—8 of the shoe, which are preferably the uppermost eyes. The lace is threaded through the eyes 7 and 8 and when 55 drawn tight causes the strap 2 to bind firmly around the instep from the heel, thus causing the upper portion of the shoe to fit snugly about the foot and instep of the wearer instead of bulging away therefrom and becoming unsightly as well as uncomfortable, 60 as is the case in present constructions.

65 From the foregoing description the nature and value of the present invention will be fully apparent to those skilled in the art to 70 which the same appertains.

Having thus fully described my invention, what I claim as new and desire to secure by Letters Patent is:

75 1. In a shoe, a strap interposed between the upper and lining of said shoe and adapted to extend upwardly around the arch from the shank, the end of said strap extending through openings in said lining and being provided with holes through which 80 the shoe lace may be threaded.

85 2. In a shoe, a strap interposed between the upper and lining of said shoe and adapted to extend upwardly around the arch from the shank, the end of said strap extending through openings in said lining and being provided with holes through which the shoe laces may be threaded, said holes being disposed so as to fall short of the corresponding shoe eyes before the lace is tightened.

HENRY DENNERT.
